THOMAS J. LITTLE, JR., OF WOODBURY, NEW JERSEY, ASSIGNOR TO WELSBACK LIGHT COMPANY, OF GLOUCESTER CITY, NEW JERSEY, A CORPORATION OF NEW JERSEY.

PILOT-LIGHTING DEVICE.

1,204,996.

Specification of Letters Patent. Patented Nov. 14, 1916.

Application filed January 26, 1916. Serial No. 74,361.

To all whom it may concern:

Be it known that I, THOMAS J. LITTLE, Jr., a citizen of the United States, residing at Woodbury, in the county of Gloucester and State of New Jersey, have invented a new and useful Improvement in Pilot-Lighting Devices, of which the following is a full, clear, and exact description, reference being had to the accompanying drawings, forming part of this specification, in which—

Figure 1 is a front view of one form of gas lamp with one form of my improved pilot light attached. Fig. 2 is a sectional view of the pilot-light on an enlarged scale, and Figs. 3 and 4 are sectional views on the lines III—III and IV—IV, respectively, of Fig. 1.

My invention relates to pilot-lights for gas burners and is designed to provide an improved pilot-lighting device which will effectively overcome the difficulties heretofore incident to such devices.

It has been common in connection with gas burners to provide a small constantly-burning pilot-light which, when the gas is turned on, will ignite the burner. The difficulty with small pilot lights has been that drafts of air will often extinguish them so that when the gas is turned on it is not ignited. The draft of air in such cases goes in two ways. First, by mechanically deflecting the gas stream away from the orifice; and, second, by the cooling effect which reduces the temperature to a point where the gas will not reignite. I have overcome these difficulties and produced a pilot lighting device which will not be extinguished by any ordinary drafts such as may occur in rooms or inclosures. In fact, I have found that with my device, a wind current of even sixteen miles an hour will not completely extinguish the pilot light so that it will not re-light on cessation of the wind current.

In carrying out my invention, I provide at the outlet or tip of the pilot tube, a loose irregular mass of non-metallic fibrous material or filaments, preferably non-metallic in character, and of low heat radiating properties, and which also acts to mechanically keep off the wind currents. This mass of fibrous material acts in two ways to prevent drafts from extinguishing the flame so that it will not re-light. First, mechanically by the protection afforded to the flame which is partly within the fibrous mass, and, sec-

ond, by maintaining high temperature due to its low heat radiating characteristics. I also preferably employ fibrous material which has some catalytic action in causing the combustion of the gas and air. As a result of experimenting in this line, I find that ordinary incandescent mantle material is peculiarly adapted for this purpose when placed in a mass at the mouth of the pilot light tube or tip and, so far as I have found, the best proportion of light salts for such fabrics is about 99½ per cent. of thorium and about ½ per cent. of cerium.

Pure thorium salts may be used, but fibers thus impregnated are not as efficient as those with a small percentage of thorium added. I also find that there should be a relatively small percentage of cerium used as an increase in its percentage tends to increase the heat radiation and thus lower the temperature of the mass. It will be understood, however, that a large range of salts or mixtures may be used for impregnating the fabric within the scope of my invention.

The fibers impregnated with lighting salts are especially efficient in pilot lighting devices because they give a considerable catalytic action such as above described. It is well known that in the ordinary incandescent mantle lamp if the gas is turned off and then turned on again within a certain small period of time, there will be sufficient catalytic action to re-light the gas; and I, therefore, prefer such a fabric for my new purpose on account of this property, as well as its highly valuable property of low heat radiation. I also believe that there is a surface combustion action taking place in the mass of fibers similar, to some extent, to that in ordinary surface combustion burners where gas under pressure is burned in small interstices of a porous mass. While in the ordinary surface combustion method it is necessary to mix with the gas substantially the correct amount of air required for complete combustion therewith, and in accordance with my invention no air need be mixed with the pilot light gas, yet the very small amount of gas used and distributed among the mass of fibers is apparently able to obtain the requisite amount of air for surface combustion within the mass.

For the best efficiency of my improved pilot lighting device, I prefer to leave the mass of fibers open to the atmosphere

around the active portions thereof so that air can be drawn in to combine with the gas within the mass. This is quite important since, if the mass were inclosed in a cup, the 5 action would be greatly impaired.

I have shown and described a pilot-lighting device applied to a lamp known in the trade as the C. E-Z lamp, it being understood that my invention is not limited to this lamp, 10 but may be applied to any gas burner whether used for lighting, heating or otherwise.

Referring to the accompanying drawings, the reference character 2 designates a 15 gas supply tube, 3 the control valve, and 4 the usual hood having air inlets for the Bunsen burner tube 5. This Bunsen tube is vertically arranged and has connected to the upper end thereof a manifold 6, with 20 a plurality of laterally and downwardly directed burner arms 7; the lower ends of these burner arms are supplied with tips 8 to which are connected mantles 9.

10 designates the pilot tube which, in the 25 form shown leads raw gas up to the pilot tip 11, and 12 is a control valve therefor. The pilot tip 11 is preferably removable and slips on the upper end of the pilot tube, and is held by friction. In the form shown, a loose 30 irregular mass of ordinary incandescent mantle fabric 13 is tied around the pilot light tip by a heat resisting cord or wire 14. This may be done simply by winding a strip of the fabric material around the 35 tip and then tying it in place.

In order to ignite the mixture issuing from the several burner tips, I provide means forming an igniter flame or flames around the mixer tube and preferably at or 40 adjacent to the level of the mouths of the burner tips. In the form shown, this igniter is formed by a surrounding sleeve or skirt 15, the lower part of which is of 45 larger diameter than the external diameter of the mixing tube, forming an annular cavity which communicates with the mixer tube through holes 16. This skirt or ring will provide an annular flame fed by the mixture and ignited by the pilot light, 50 which will burn continuously during the operation of the lamp. However, even this annular flame in some cases does not absolutely insure ignition of the mixture issuing 55 from every tip, in case a mantle is injured or destroyed. To further insure such action, I provide the holes or jet openings 17 below the lower edge of the sleeve and preferably registering with the burner tips. These jet openings are preferably the same 60 in number as the burner tips and placed adjacent to them so that the jets of flame projecting through these holes will insure ignition at each burner tip.

When the device is in use, a small flame 65 burns within the mass of fibrous material 13

and may or may not appear beyond it. The flame may be, and preferably is, very small, and in the use of my invention the amount of gas consumed by the pilot may be greatly reduced. If a draft occurs, the 70 flame may be driven to the side of the fibrous mass opposite to that from which the draft comes, but the flame will actually remain, even under a considerable draft above that which would normally occur in any 75 enclosed room. On cessation of the draft, the flame will at once distribute and rekindle again through the mass, aided by the catalytic action, if the preferred material is employed.

The advantages of my invention will be apparent to those skilled in this art, since the great drawback and danger to pilot-light ignition is overcome. The consumption of gas by the pilot-light may be considerably reduced, the danger of blowing out is avoided and a removable tip supplied with my invention may be sold for attachment to any pilot-light tube.

Many different materials may be used for 90 the fibrous mass and impregnation with the salts of rare earths may or may not be used, although I prefer to employ them. The pilot-light tube may be supplied with raw 95 gas or with a mixture of gas and air and may be either vertical, horizontal or inclined, with the pilot-light at the lower or upper end. The fibrous mass may be secured to the pilot tip or tube in many different ways and other variations may be made without 100 departing from my invention.

If the fibers or fabrics are impregnated with rare earths, the fabric may be burned out in the use of the pilot-light or at the 105 factory before it is sold.

I claim:

1. A pilot light tip having a fuel outlet, and a loose irregular mass of non-combustible fibrous material at said fuel outlet to enmesh the flame, said fibrous material being of low heat radiating qualities so that the temperature of the mass will be maintained above the kindling point of the gas, substantially as described.

2. The combination with a pilot light tip, 115 of a loose irregular mass of fibrous material composed at least in part of rare earths, said mass being in substantially close contact with the open end of the tip, substantially as described.

3. The combination with a pilot light tip, 120 of a loose irregular mass of fibrous material composed at least in part of thorium compounds, said mass being in substantially close contact with the open end of the tip, substantially as described.

4. The combination with a pilot light tip, 125 of a loose irregular mass of fibrous material composed at least in part of thorium and cerium compounds, said mass being in sub- 130

stantially close contact with the open end of the tip, substantially as described.

5. The combination with a gas burner of a pilot light arranged to burn constantly and ignite the burner, said pilot light having a loose irregular mass of non-combustible fibrous material which enmeshes the flame, said fibrous material being of sufficiently low heat radiating properties so that

the temperature of the mass will be maintained above the kindling point of the gas, substantially as described. 10

In testimony whereof, I have hereunto set my hand.

THOMAS J. LITTLE, JR.
